SYSTEM OF OPERATING FLUID-OPERATED PUMPS

Clarence James Coberly, Los Angeles, Calif., assignor to Roko Corporation, Reno, Nev., a corporation of Nevada

Application December 16, 1935, Serial No. 54,557

23 Claims. (Cl. 103—46)

My invention relates to the art of pumping natural fluids from wells, and relates in particular to the operation of a number of pumps in different oil wells of an oil field.

5 It is an object of the invention to provide a system of pumping a plurality of wells in an oil field by use of hydraulic means so as to avoid the difficulties encountered in the use of sucker rod pumps and to minimize the cost of the pumping 10 operation. Owing to the elasticity of sucker rods now extensively employed in the operation of oil well pumps, the overall efficiency of the pumping equipment is very low. In addition to the losses due to the excessive power consumption, there 15 are also losses resulting from breakage of the sucker rods and shut-downs during the pulling and replacing of pumping equipment.

It is an object of my invention to provide a pumping system for a plurality of wells in which 20 each well is equipped with a fluid-operated pump having an operating fluid inlet and a discharge outlet for the production of the well, together with means for diverting a portion of the production through a treating device which converts 25 a portion of the oil field production into a fluid suitable for use as an operating fluid for the fluid-operated pump units. This treatment, for example, may consist of filtering the oil to remove sediment and abrasive substances therefrom and otherwise changing the characteristics 30 of the oil. If the oil is too thick, its viscosity may be lowered by heating. If the volatile constituents of the oil are too great, the treating process may include the removal of part of the 35 volatiles. If the oil is not of sufficient lubricating character for the lubrication of the parts of the pump unit with which it comes in contact, the treating thereof to produce a suitable operating fluid may include the addition of lubricant.

40 In fact, under this treatment of the production fluid to produce an operating fluid, all things necessary to produce a suitable operating fluid may be done as required by the characteristics of the production oil, conditions in the wells being 45 pumped, etc. For example, one or more of the wells may have a tendency to form an emulsion. The general process herein referred to as "treating" may include the addition of demulsifying agents which pass with the operating fluid and 50 are combined with the oil pumped from the well so as to be intermixed therewith and rise through the production pipe to the surface of the ground.

The marked rise in overall pumping efficiency 55 to be obtained by the use of a fluid-operated pump unit in a well is now definitely established. My present invention has for an object to further increase the pumping efficiency by the simplification and consolidation of equipment so that maximum production is obtained with minimum 60 equipment and operating expense.

It is an object of the invention to provide a pumping system of the character above described, in which a source of operating fluid is maintained, this operating fluid being placed under compression by pumping means and delivered to the individual wells of a pumping group. In the invention means are provided for controlling the flow of operating fluid to the individual pump units so that the pumping action accomplished in each well will be controlled in accordance with the 10 requirements of the well and will be independent of the pumping operations of the remaining wells in the pumping system.

15 It is an object of the invention to provide a system as set forth in the preceding paragraph in which a single pressure pumping unit is employed to draw the operating fluid from the supply thereof and deliver the same under pressure through a pressure header connected with the inlet pipes of the various pumping units, there 20 being control means connected with the inlet pipes of the pump units for controlling the pumping actions effective in the individual wells. In a pumping system of this character, some of the wells may be pumping from different levels than 25 other of the wells, and accordingly the pressure of the operating fluid required by the pump units will differ in accordance with the depth from which the oil is being pumped. The invention comprehends means for increasing and decreasing 30 the pressure of the operating fluid in accordance with the requirement of each well.

35 A further object of the invention is to provide a simple form of control means which forms a part of the invention.

Further objects and advantages of the invention will be made evident throughout the following part of the specification.

Referring to the drawings, which are for illustrative purposes only,

40 Fig. 1 is a schematic view showing a preferred form of the invention.

Fig. 2 is an enlarged cross section on the line 2—2 of Fig. 1, showing details of construction of the differential-pressure control means forming 45 a part of the invention.

Fig. 3 is a section on the plane indicated by the line 3—3 of Fig. 2.

Fig. 4 is a fragmentary view showing a means for changing the pressure-volume characteristics 50 of the operating fluid, adapted to be substituted for a part of the equipment shown in Fig. 1.

Fig. 5 is a diagrammatic view showing another embodiment of the invention in which the compressor means of the invention is embodied in a 55 plurality of pressure pumps.

Fig. 6 is a diagrammatic view showing a form 60 of the invention in which a control means of adjustable character is placed in the well near the pump unit.

In Fig. 1 I show wells 11 and 12 indicating the manner in which a plurality of wells in a producing field may be incorporated in a single pumping system. The details shown in conjunction with the well 11 indicate the general arrangement of pumping equipment to be employed in each of the wells of the pumping system. In the well 11 is a fluid-operated pump unit 13 of the character disclosed in my co-pending Patent No. 2,081,223, issued May 25, 1937, and entitled "Fluid operated deep well pump", such pump unit 13 having a pump portion 14 connected to a fluid-operated motor 15 which is in turn connected through a bleeder 15a with an operating fluid inlet pipe 16. In the preferred practice of the invention the pump unit 13 is placed near the lower end of the well, and the fluid inlet pipe 16 extends upwardly from the pump unit 13 through a discharge pipe 17 and through a suitable casing head 18 which is connected to the upper end of the discharge pipe 17 and has an outlet 19 for the issue or delivery of the production of the well. The outlet 19 is connected to a production pipe or header 21. The well structure 12 also includes a pump unit designated as 13a with an inlet pipe 16a for operating fluid. The well 12 has also a production pipe 19a which delivers its production into the header 21.

A feature of the invention is to divert a portion of the production from the field and to treat such diverted portion of the production so as to convert it into or render it suitable for use as operating fluid for the fluid-operated motors of the pumping system. Whether or not this portion is taken from the production of all of the wells or part of the wells is immaterial in the practice of the invention. Illustrative of the general principle here involved, I show the header 21 connecting with the inlet 22 of a treating device 23 having a lower chamber 24 and an upper chamber 25. The treating device 23 is preferably a filter such as is shown and described in detail in the patent to Coberly, et al., No. 2,046,769, issued July 7, 1936, in which I was a co-inventor. In the treating device 23, a standpipe 26 extends upwardly from the lower chamber 24 into a shell 27 mounted upon, but separate from, the upper chamber 25. The main portion of the production fluid delivered by the header 21 passes upwardly from the lower chamber 24 through the standpipe 26. From the upper end 28 of the standpipe 26 the production fluid passes downwardly within the shell 27 and is then carried through piping 29 to any suitable means for disposing of the production fluid, such, for example, as storage tanks or oil transmission pipe lines. The head of oil in the standpipe 26 places a pressure on the body of oil 31 contained in the lower chamber 24, this pressure forcing or diverting a portion of the oil upwardly through a filter 32 into the upper chamber 25, the filter 32 performing a treatment of the diverted oil consisting of the removal of sediment and abrasives therefrom. To control the quantity of oil which passes through the filter 32 into the upper chamber 25, a second standpipe 34 is provided, the upper end of which passes upwardly into the shell 27 to a point slightly higher than the upper end 28 of the standpipe 26.

The invention includes means for conducting the operating fluid 35 from the upper chamber 25 to the inlet pipes 16-16a of the fluid-operated pumps of the pumping system, this conducting means including an operating fluid de-

livery header 36 with an associated pressure pump 37 which in the form of the invention shown receives the operating fluid from the upper chamber 25 through a pipe 38. As taken from the chamber 25, the operating fluid is under a pressure determined by the pressure at which the fluid is delivered in the line 28, the height of the pipe 28, and the differential pressure across the filter medium through which it must flow. The pressure of the operating fluid as it is taken from the chamber 25 may be relatively low, and in such case in being conducted to the different pump units of the pumping system it may be desirable to increase the pressure thereof sufficiently to operate the unit in the well 15 having the greatest lift, and the flow must be divided to suit the requirements of the individual pump units. The pump 37 accomplishes these functions by increasing the pressure of the operating fluid which is then conducted under 20 pressure through the header 36 to each well through a control device 40 which in Fig. 1 is connected to the upper end of the inlet pipe 16 of the pump unit 13. The control device 40 is of such character that it controls the volume of 25 operating fluid which passes to the pump unit 13 and may reduce the pressure thereof.

The control device 40 is constructed as shown in Figs. 2 and 3. It includes a body 41 having a central bore 42 from which a lateral outlet passage 43 extends. A flange connector 44 is secured in alignment with the opening 43 so as to connect the pipe 16 therewith. Inserted in the bore 42 is a tubular member 45 which is of such length that a chamber 46 is left in the forward 35 or leftward end of the bore. The leftward end of the tubular member 45 is provided with a primary bore 47 and with lateral openings 48 communicating with the discharge passage 43. A head 49 closes the leftward end of the bore 42, this head 49 being bolted in place and having an opening 51 in alignment with the bore 42 but being of smaller diameter than the bore to provide a shoulder 52. In crossing relation to the opening 51, the head 49 is provided with an opening 53, in one end of which a valve seat 54 is formed leading through an inlet passage 56 to a flange fitting 55 which is adapted to be bolted to the head 49 for the purpose of connecting the operating fluid header 36 to the inlet passage 56 of the control device 40. The upper or opposite end of the opening 53 is threaded at 57 to receive a valve member 58 having the lower end 59 thereof tapered for engagement with the valve seat 54. For moving the valve member 58 relative to the seat 54, a squared stem 61 is provided thereon, which stem 61 extends into a socket 62 formed in a member 63 having a stem 64 which projects within an opening 65 in a cap member 66 bolted on the upper end of the head 49. The stem 64 is provided with a projection 67 prepared to receive a wrench. The member 63 is provided with an outwardly faced shoulder 68 which bears against a packing ring 69 carried in an annular recess 71 formed at the inner end 65 of the opening 65 of the cap 66. To transmit fluid pressure to the inner face of the member 63, an opening 72 is formed longitudinally through the side portion of the member 63.

Slidable in the leftward end of the bore 42 is 70 a piston member 73 which is secured to the leftward end of a tubular stem 74 having a pin 75 therein provided with a pointed and diametrically reduced rightward end 76 with radial openings 77 communicating with an axial opening 78 ex-

tending to the leftward end of the stem. The openings 77 and 78 provide a passage through which fluid may flow from the space 51 into the rightward end of the bore to balance the fluid pressure applied to the opposite ends of the tubular stem 74. The end 76 of the pin 75 engages a plate 79 which rests against the leftward end of an adjustment spring 81 which passes through a rotatable sleeve 82 to a block 83 having a laterally extending pin 84 therein. The ends of the pin 84 project through spiral grooves 85 in the sleeve 82 and into longitudinal slots 86 in the rightward end of the tubular member 45 to prevent rotation of the pin 84 and the block 83 but permit movement thereof in the direction of the axis of the bore 42. The sleeve 82 is rotatable for the purpose of moving the block 83 in axial direction as the result of the spiral grooves 85 moving with relation to the end portions of the pin 84. The sleeve 82 is closed at its rightward end and is provided with an outwardly projecting stem or extension 87 which passes through an opening 88 in a cover plate 89 on the rightward end of the body 41. At a point within the opening 88 the stem 87 is provided with a shoulder 91 which bears against a packing ring 92 which rests against an inwardly faced shoulder 93 provided by the cover plate 89. The outer end of the stem has a projection 94 prepared for engagement with a wrench adapted to turn the sleeve 82, and a dial plate 95 may be secured to the stem 87, this dial plate 95 being set in a recess 96 formed in the outer portion of the cover plate 89 and being calibrated to indicate various settings of the control device. Such calibrations may be in terms of barrels per day of operating fluid delivered through the inlet pipe 16, or the calibrations may indicate the capacity of the pump unit 13 resulting from the quantity of operating fluid permitted to flow thereto by the control device 40. The piston member 73 is provided with openings 97 forming metering orifices so that as the fluid delivered to the device through the inlet passage 56 passes from the opening 51 of the head 49 through the orifices 97 into the chamber 46, there will be a drop in pressure to form a pressure differential on the inner and outer sides of the piston member 73 tending to move the piston member and the stem 74 rightwardly against the leftward pressure of the spring 81. From the chamber 46 the operating fluid passes through an annular space 98 in the leftward end of the tubular member 45 to the radial passages 48 and finally through the outlet passage 43 to the pipe 16 leading to the pump unit 13. A wear ring 99 is provided in an inset recess in the leftward end of the tubular member 45, and the stem 74 and a valve sleeve member 101 carried thereon have a close sliding fit in the wear ring. The pressure differential between the pressure in the opening 51 and the pressure in the chamber 46 plus the force exerted by the spring 81 determine the position of the piston 73, the stem 74, and the valve sleeve 101. Accordingly, the pressure tending to move the piston 73 to the left, as seen in Fig. 2, may be adjusted by rotating the sleeve 82 having the spiral grooves 85 therein to give the desired compression to the spring 81. Any increase in fluid pressure in the pipe 36 will be transmitted to the fluid in the opening 51 to increase the force tending to move the piston 73 to the right, and if this force exceeds the leftward counter forces exerted by the fluid pressure in the chamber 46 and by the spring 81, the piston 73 will move to the right. Rightward move-

ment of the piston 73, however, causes the valve sleeve 101 to also move to the right towards a close fit with the wear ring 99 which tends to close the annular space 98 normally between the valve sleeve and the wear ring. Partial closure of the space 98 restricts the flow of fluid from the opening 51 to the radial passages 48, so as to maintain the discharge through the outlet 43 at a substantially constant rate of flow. When the fluid pressure in the opening 51 drops below the leftward pressure exerted by the fluid in the chamber 46 and by the spring 81, the piston 73 will move to the left so as to open the annular space 98 to permit an increased flow of fluid therethrough.

Likewise, should there be a reduction in fluid pressure in the piping 16 and the opening 43, a momentary drop in pressure in the chamber 46 would result, thereby increasing the pressure differential on the leftward and rightward faces of the piston 73 to cause a similar rightward movement of the piston 73 and the valve sleeve 101.

To show the pressure of fluid being delivered into the pipe 16, the control device may be provided with a pressure gauge 102. The gauge 102 has an inlet 103 into which a screw 104 is threaded. This screw 104 passes through an opening 105 in a connector ring or link 106. The ends of the opening 105 are counterbored to receive gasket rings 107 and 108 which respectively engage the lower end of the inlet 103 and a shoulder 109 formed on the upper part of the head of the screw 104. The link 106 has another opening 111 spaced from the opening 105, and a screw 112 passes through the opening 111 into threaded engagement with an opening 113 formed in the body 41 so as to communicate with the passage 43 thereof. The lower end of the opening 113 is formed with a counterbore 110 to receive a packing ring 114, and an axial flange 115 is provided on the link 106 to extend into the counterbore 110 and bear against the packing ring 114. The lower end of the opening 111 is formed with a counterbore 115a into which a packing ring 116 is compressed by a shoulder 117 formed on the upper part of the head 118 of the screw 112. By the use of the gasket or packing rings shown, both ends of each opening are sealed against escape of fluid under pressure.

The screw 112 has an axial opening 119 leading downwardly from the upper end thereof and connecting with an opening 121 of larger diameter which leads upwardly from the lower end of the screw 112. The opening 121 has a valve needle 122 threaded therein so as to enter the lower end of the opening 119, this needle 122 being provided with packing means 123 to prevent leakage therearound. Radial holes 124 lead outwardly from the upper part of the opening 121 to carry fluid under pressure into the space 125 in the opening 111 around the body of the screw 112. From the annular space 125 the fluid is carried through a hole 126, diagonally drilled in the link 106, to the annular space 127 formed in the opening 105 around the body of the screw 104. A radial hole 128 in the screw 104 communicates with an axial opening 129 leading upwardly to the upper end of the screw 104 to the mechanism of the pressure gauge 102, not shown, but which may be of conventional design.

The reduction of pressure through the control device 40 is accompanied by a pressure loss which is not of great importance where all of the wells of the system are of nearly the same depth, but where one or two of the wells are at a greatly

different depth from the remaining wells of the system, it may be desired to avoid this loss in efficiency. My invention comprehends control means in the system whereby the pressure-volume characteristics of the operating fluid delivered to one or more of the wells may be changed without great loss of efficiency, even though the change in the characteristics may be quite large. In this instance the control means embodies a fluid transformer 131, Fig. 1, for reducing the pressure and increasing the volume of fluid delivered, and consists of a fluid-operated motor 132 of any suitable design having its shaft 133 connected to a pressure pump 134 so as to drive the same. Pressure fluid from the header 36 is delivered through piping 135 to operate the fluid motor 132, and the discharge from the motor 132 is delivered through a pipe 136 into the pipe 16a which leads to the pump unit 13a in the well and which also has a control device 40 connected therein.

The operating fluid pipe 138 carries clean fluid from the chamber 25 to the inlet of the pressure pump 134, and this operating fluid is discharged from the pump 134 through a pipe 139 into the pipe 16a to be combined with the fluid which has been discharged into the pipe 16a by the motor 132. In this way the power represented in the drop in pressure of fluid through the motor 132 is employed to compress other operating fluid, and the efficiency losses thereby occasioned are limited to frictional losses of the motor 132 and the pump 134. The fluid flow-pressure transformer 131 may have the motor 132 and the pump 134 thereof so proportioned that the operating fluid passing through the pipe 16a may have any desired pressure lower than the pressure of the fluid in the header 36, so that the requirement of any shallow well in the pumping system may be met 40 without undue efficiency losses.

As shown in Fig. 4, the motor 132 and the pump 134 may be connected so as to produce a higher pressure in the pipe 16a. In this form of the invention the pipe 135 leading from the header 36 is connected to the inlet of the motor 132, and is also connected through a pipe 141 with the inlet of the pump 134. The discharge of the motor 132 is connected through a pipe 142 with the pipe 138 leading to the fluid supply chamber 25, and the discharge of the pump 134 is connected through a pipe 143 with the pipe 16a having a control valve 40 therein. In this hookup the motor 132 and the pump 134 both receive operating fluid under pressure. The operating fluid received under pressure by the pump 134 is increased in pressure by the pump and is discharged at such increased pressure into the pipe 16a leading to the pump 13a in the well. By the use of the pressure transformer shown in Fig. 4, the operating fluid under pressure in the header 36 may be increased to any desired high pressure for the operation of a pump set in a deep well, without excessive losses in efficiency.

As shown in Fig. 6, the adjustable control means 65 for the individual pump units in the wells of a pumping system may be placed in the lower parts of the wells, so that such control means will not only serve as a means for controlling the production, but also as means for preventing the racing 70 of the pump unit should the pumping load be removed, as, for instance, by the entrance of a pocket of gas into the pump element of the pump unit. This adjustable control means is an improvement on the control mechanism shown in 75 my co-pending application, Serial No. 720,059,

filed April 11, 1934, to which reference is hereby made. This control member, indicated by 40b, is provided with a body 144 of tubular form internally threaded at its upper end 145 for connection to the lower end of the tubing bleeder 15a 5 disposed at the lower end of the pipe 16 which carries the operating fluid down through the well to the pump unit 13. Employing the same principles of construction as the device shown in Figs. 2 and 3, the body 144 has an interior space 147 10 in which a piston 148 is vertically movable. This piston 148 has a tube 149 extending downwardly therefrom into the diametrically reduced bore 151 of the body 144. A spring 153, bearing against the lower end of the tube 149, tends to move the tube 15 and piston 148 upwardly. A pressure differential 15 to move the piston downwardly is produced by metering orifices 155 in the piston through which the operating fluid must pass from the chamber 156 above the piston 148 to the chamber 157 20 formed below the piston 148. An increase in pressure above the piston 148, or a decrease in pressure below the piston, will increase the pressure differential and move the piston downwardly against the action of the adjustment spring 153, 25 causing valve openings 158 in the wall of the tube 149 to move downwardly relative to the upper end 159 of the bore 151, thereby restricting at this point the area of passage for the fluid which passes through the openings 158 and then through 30 radial passages 160 and down through longitudinal passages 161 which extend to the lower end of the body 144 and connect with a chamber 162 in a tubular part 161a threaded at 162a to the lower end of the body 144.

The lower end of the spring 153 rests against an adjusting plug 163 which is screwed into threads 164 at the lower end of the bore 151. The plug 163 has a flattened tongue 165 which projects downwardly in through a slot 166 formed 40 in the upper end of a body 167 which is disposed within the tubular member 161a, and which body 167 is threaded into the upper end of the motor 15 which forms a part of the pump unit 13. The body 167 has passages 168 therein 45 through which the operating fluid may flow from the chamber 162 into the other end of the fluid motor to operate the pump mechanism. The body 144 of the control valve and the member 161a thereof are rotatable relative to the body 167 which is secured in the upper end of the motor. The adjusting plug 163, being connected through the use of the tongue 165 with the body 167, remains stationary when the operating fluid delivery pipe 16, and likewise the valve body 144, 55 are turned with the result that by rotation of the valve body 144, the adjusting plug 163 may be caused to screw upwardly or downwardly in the lower end of the bore 151 so as to change the compression of the spring 153 and thereby 60 change the adjustment of the control valve. This form of the control valve is adjusted by turning the fluid delivery pipe 16 until a desired flow of oil from the well is obtained. Packing means 169 are provided between the body 167 and the member 161a to prevent leakage of fluid from the space 162.

The form of control valve shown in Fig. 6, which permits its location directly above the pump unit, performs a dual function. It not 70 only serves as a means for controlling the production of the pumping equipment, but also serves as a governor for preventing excessive speed in the operation of the pump unit 13. Should a pocket of gas enter the pump element 75

of the unit 13 so that the pumping load would be suddenly reduced, there would be a tendency for the motor 15 to race due to removal of the pumping load. This racing of the pumping device cannot occur when the control valve is employed as shown in Fig. 6 for the reason that any drop in pressure in the lower chamber 157 will increase the pressure differential applied to the piston 148 with the result that the piston 148 and its stem 149 will move downwardly so as to shut down the valve formed by the passages 158 in the stem 149, controlling the flow of operating fluid which is delivered to the pump motor 15 and thereby preventing operation of the same at an excessive speed which might be harmful to the reciprocating parts of the pumping mechanism. The valve illustrated in Figs. 2 and 3 functions in the same manner, but since a large volume of fluid may be contained in the pressure line 16 between the valve and the pump unit, the expansion of this fluid, if the load is released from the pump, would be sufficient to operate the pump 15 a number of complete cycles at high speed, and the valve located at the top of the well 25 could not control this rate of expansion.

In Fig. 5 I show a form of the invention in which the compressor means for the operating fluid are disposed near the wells in which the pump units 13 are placed. The discharge pipes 30 17 of a part of the wells are shown connected to a production header 170 leading toward a means for oil disposal consisting of a storage tank 171. The remaining wells of the pumping system may, if desired, be connected to other oil disposal means, and illustrative of this I have shown the production pipe 169 of the third well not connected to the production header 170. The header 170 is shown connected to an oil treater 172 in which a part of the production is diverted 40 through a pipe 173 to an operating fluid supply tank 174. A conducting means for the operating fluid leads from the tank 174 to the inlet pipes 16 of the pump units 13. The conducting means consists of a pipe 175 and pressure pumps 176, 45 each of which has its own drive means in the form of a motor 177. The operation of each pump 176 may be individually controlled to suit the requirements of the well with which it is associated.

50 Although I have herein shown and described my invention in simple and practical form, it is recognized that certain parts or elements thereof are representative of other parts, elements, or mechanisms which may be used in substantially the same manner to accomplish substantially the same results; therefore, it is to be understood that the invention is not to be limited to the details disclosed herein but is to be accorded the full scope of the following claims.

60 I claim as my invention:

1. A well pumping system of the character described, including: a plurality of fluid-operated pump units placed so as to pump from a plurality of wells, there being a pressure fluid inlet pipe connecting with the fluid-operated motor of each of said pump units, and there being a production discharge member associated with each pump unit; piping for receiving the production from said production discharge member; means for diverting a portion of said production; a treating device for converting said diverted portion of the production into an operating fluid for said pump units; and means for conducting the operating fluid to said pressure fluid inlet pipes 65 of said pump units, said conducting means in-

cluding individual compressor means in each of said fluid inlet pipe lines for placing said operating fluid under pressure so that it will operate said fluid-operated motors of said pump units.

2. A well pumping system of the character described, including: a plurality of fluid-operated pump units placed so as to pump from a plurality of wells, each of said pump units requiring operating fluid having flow characteristics different from the other of said units, there being a pressure fluid inlet pipe connecting with the fluid-operated motor of each of said pump units, and there being a production discharge member associated with each pump unit; piping for receiving the production from said production discharge member; means for diverting a portion of said production; a treating device for converting said diverted portion of the production into an operating fluid for said pump units; means for conducting the operating fluid to said pressure fluid inlet pipes of said pump units, said conducting means including individual compressor means in each of said fluid inlet pipe lines for placing said operating fluid under pressure so that it will operate said fluid-operated motors of 25 said pump units; and control means connected with each of said pressure fluid inlet pipes for separately regulating the flow of operating fluid to the individual pump units and maintaining the flow to each of said units substantially constant. 30

3. A well pumping system of the character described, including: a plurality of fluid-operated pump units placed so as to pump from a plurality of wells, there being a pressure fluid inlet pipe connecting with the fluid-operated motor of each of 35 said pump units, and there being a production discharge member associated with each pump unit; piping for receiving the production from said production discharge member; means for diverting a portion of said production; a treating device for converting said diverted portion of the production into an operating fluid for said pump units; means for conducting the operating fluid to said pressure fluid inlet pipes of said pump units, said conducting means including individual compressor means in each of said fluid inlet pipe lines for placing said operating fluid under pressure so that it will operate said fluid-operated motors of said pump units; and control means connected to one of said pressure fluid inlet pipes for 40 positively regulating the pressure-volume characteristics of the operating fluid delivered to one of said pump units as desired independently of the load on said unit. 45

4. A well pumping system of the character described, including: a plurality of fluid-operated pump units placed so as to pump from a plurality of wells, there being a pressure fluid inlet pipe connecting with the fluid-operated motor of each of 55 said pump units, and there being a production discharge member associated with each pump unit; piping for receiving the production from said production discharge member; means for diverting a portion of said production; a treating device for converting said diverted portion of the production into an operating fluid for said pump units; means for conducting the operating fluid to said pressure fluid inlet pipes of said pump units, said conducting means including individual compressor means in each of said fluid inlet pipe lines for 60 placing said operating fluid under pressure so that it will operate said fluid-operated motors of said pump units; and a metering device connected to one of said inlet pipes so that operating fluid will 65 pass therethrough said metering device. 70

a constant flow of operating fluid to one of said pump units independently of and different from other pump units included in said pumping system.

5. A well pumping system of the character described, including: a plurality of fluid-operated pump units placed so as to pump from a plurality of wells, there being a pressure fluid inlet pipe connecting with the fluid-operated motor of each 10 of said pump units, and there being a production discharge member associated with each pump unit; piping for receiving the production from said production discharge member; means for diverting a portion of said production; a treating 15 device for converting said diverted portion of the production into an operating fluid for said pump units; means for conducting the operating fluid to said pressure fluid inlet pipes of said pump units, said conducting means including individual 20 compressor means in each of said fluid inlet pipe lines for placing said operating fluid under pressure so that it will operate said fluid-operated motors of said pump units; a casing connected between one of said inlet pipes and said conducting means, 25 said casing having its intake connected to said conducting means and its outlet connected to said inlet pipe and having means therein movable in response to changes in the pressure differential between said intake and said outlet; and valve 30 means operatively connected to said movable means adapted to vary the flow of the operating fluid delivered to the pump unit connected to said inlet pipe.

6. A well pumping system of the character described, including: a plurality of fluid-operated pump units placed so as to pump from a plurality of wells, there being a pressure fluid inlet pipe connected with the fluid-operated motor of each 35 of said pump units, and there being a production discharge member associated with each pump unit; piping for receiving the production from said production discharge member; means for diverting a portion of said production; a treating device for converting said diverted portion of the 40 production into an operating fluid for said pump units; means for conducting the operating fluid to said pressure fluid inlet pipes of said pump units, said conducting means including compressor 45 means for placing said operating fluid under pressure so that it will operate said fluid-operated motors of said pump units; a casing connected between one of said inlet pipes and said conducting means; a movable member in said casing dividing the same into a pair of chambers, one of which 50 is connected to said inlet pipe, and the other of which is connected to said conducting means; orifice means connecting said chambers and causing a drop in pressure between said chambers so as to produce a pressure differential tending to 55 move said movable member; and valve means operatively connected to said movable means adapted to vary the pressure-volume characteristics of the operating fluid delivered to the pump unit connected to said inlet pipe.

7. A well pumping system of the character described, including: a plurality of fluid-operated pump units placed so as to pump from a plurality of wells, there being a pressure fluid inlet pipe connecting with the fluid-operated motor of each 60 of said pump units, and there being a production discharge member associated with each pump unit; piping for receiving the production from said production discharge member; means for diverting a portion of said production; a treating 65 device for converting said diverted portion of the

production into an operating fluid for said pump units; means for conducting the operating fluid to said pressure fluid inlet pipes of said pump units, said conducting means including compressor means for placing said operating fluid under pressure so that it will operate said fluid-operated motors of said pump units; a casing connected between one of said inlet pipes and said conducting means; a movable member in said casing dividing the same into a pair of chambers, one 10 of which is connected to said inlet pipe, and the other of which is connected to said conducting means; orifice means connecting said chambers and causing a drop in pressure between said chambers so as to produce a pressure differential tending to move said movable member; valve means operatively connected to said movable means adapted to vary the pressure-volume characteristics of the operating fluid delivered to the pump unit connected to said inlet pipe; and resilient 15 means for resisting the movement of said movable member.

8. A well pumping system of the character described, including: a plurality of fluid-operated pump units placed so as to pump from a plurality of wells, there being a pressure fluid inlet pipe connecting with the fluid-operated motor of each 20 of said pump units, and there being a production discharge member associated with each pump unit; piping for receiving the production from said production discharge member; means for diverting a portion of said production; a treating device for converting said diverted portion of the production into an operating fluid for said pump 25 units; means for conducting the operating fluid to said pressure fluid inlet pipes of said pump units, said conducting means including individual compressor means in each of said fluid inlet pipe lines for placing said operating fluid under pressure so that it will operate said fluid-operated motors of said pump units; and control means in one of said wells adjacent one of said pump units, said control means being connected to the inlet pipe of the pump unit and maintaining a substantially constant flow of operating fluid to said 30 pump unit.

9. A well pumping system of the character described, including: a plurality of fluid-operated pump units placed so as to pump from a plurality of wells, there being a pressure fluid inlet pipe connecting with the fluid-operated motor of each 35 of said pump units, and there being a production discharge member associated with each pump unit; piping for receiving the production from said production discharge member; means for diverting a portion of said production; a treating device for converting said diverted portion of the production into an operating fluid for said pump units; means for conducting the operating fluid to said pressure fluid inlet pipes of said pump units, said conducting means including individual compressor means in each of said fluid inlet pipe lines for placing said operating fluid under pressure so that it will operate said fluid-operated 40 motors of said pump units; and adjustable control means in one of said wells adjacent one of said pump units, said control means being connected to the inlet pipe of the pump unit and maintaining a substantially constant flow of operating fluid to said pump unit.

10. A fluid-operated pumping device, including: a fluid-operated pumping unit disposed in a well, there being a tubular fluid inlet member extending from said pump unit; an operating fluid 45

5 delivery pipe extending downwardly into said well; a valve casing connecting said delivery pipe to said inlet member, said casing having a valve port through which said operating fluid flows from said delivery pipe to said inlet member; a member in said casing movable in response to a decrease in the pressure of operating fluid in said inlet member and having a part which reduces the effective area of said valve port as the pressure in said inlet member decreases relative to the pressure of operating fluid in said delivery pipe; resilient means exerting a force to resist the movement of said movable member; and means operative from the top of the well to adjust 10 said resilient means so as to vary the resisting force exerted thereby.

11. A fluid-operated pumping device, including: a fluid-operating pumping unit disposed in a well, there being a tubular fluid inlet member 20 extending from said pump unit; an operating fluid delivery pipe extending downwardly into said well; a valve casing connecting said delivery pipe to said inlet member, said casing having a valve port through which said operating fluid flows from said delivery pipe to said inlet member; a member in said casing movable in response to a decrease in the pressure of operating fluid in said inlet member and having a part which reduces the effective area of said valve port as the pressure in said inlet member decreases relative to the pressure of operating fluid in said delivery pipe; spring means exerting a force to resist the movement of said movable member; and means operative from the top of the well to 30 adjust said spring means so as to vary the resisting force exerted thereby.

12. A fluid-operated pumping device, including: a fluid-operating pumping unit disposed in a well, there being a tubular fluid inlet member 40 extending from said pump unit; an operating fluid delivery pipe; a governor connecting said delivery pipe to said inlet member, and controlling the flow of operating fluid to said pump unit; and means operative from the top of the well to 45 adjust said governor so as to change the flow of operating fluid therethrough.

13. A well pumping system of the character described, including: a fluid-operated pump unit placed so as to pump from a well, including a fluid-operated production motor; a pipe connecting the intake of said production motor with a source of supply of operating fluid adapted to operate said motor; pressure means associated with said pipe and adapted to deliver said operating fluid under pressure through said pipe to said production motor; and transformer means in the line of said pipe adapted to reduce the pressure in said pipe, said transformer means including an auxiliary fluid-operated motor having its inlet connected to said pipe and having its discharge connected to said intake of said production motor, and an auxiliary pump driven by said auxiliary motor and having its discharge connected to said intake and having its inlet connected to a source of supply of said operating fluid.

14. A well pumping system of the character described, including: a plurality of fluid-operated pump units placed so as to pump from a plurality 70 of wells, each of said units including a fluid-operated production motor; a pipe connecting the intake of each of said production motors with a source of supply of operating fluid adapted to operate said motors; pressure means associated with said pipes and adapted to deliver said operating fluid under pressure through its said 75 pipe to the production motor connected thereto so as to operate said motor.

5 ating fluid under pressure through said pipes to each of said production motors; and transformer means in the line of one of said pipes leading to a specified well motor adapted to reduce the pressure in said pipe, said transformer means including an auxiliary fluid-operated motor having its inlet connected to said pipe and having its discharge connected to the intake of said specified well motor, and an auxiliary pump driven by said auxiliary motor and having its discharge connected to the intake of said specified well motor and having its inlet connected to a source of supply of said operating fluid.

15. A well pumping system of the character described, including: a fluid-operated pump unit 15 placed so as to pump from a well, including a fluid-operated production motor; a pipe connecting the intake of said production motor with a source of supply of operating fluid adapted to operate said motor; pressure means associated 20 with said pipe and adapted to deliver said operating fluid under pressure through said pipe to said production motor; and transformer means in the line of said pipe adapted to increase the pressure in said pipe, said transformer means including an auxiliary fluid-operated motor having its inlet connected to said pipe and having its discharge connected to a source of supply of 25 said operating fluid, and an auxiliary pump driven by said auxiliary motor and having its inlet connected to said pipe and having its discharge connected to said intake of said production motor.

16. A well pumping system of the character described, including: a plurality of fluid-operated pump units placed so as to pump from a plurality of wells, each of said units including a fluid-operated production motor; a pipe connecting the intake of each of said production motors with a source of supply of operating fluid adapted to operate said motors; pressure means associated with said pipes and adapted to deliver said operating fluid under pressure through said pipes to each of said production motors; and transformer means in the line of one of said pipes leading to a specified well motor adapted to increase the pressure in said pipe, said transformer means including an auxiliary fluid-operated motor having its inlet connected to said pipe and having its discharge connected to a source of supply of said operating fluid, and an auxiliary 30 pump driven by said auxiliary motor and having its inlet connected to said pipe and having its discharge connected to said intake of said production motor.

17. A well pumping system of the character described, including: a plurality of fluid-operated pump units placed so as to pump a production flow from a plurality of wells, each of said units including a fluid-operated production motor; a pipe connecting the intake of each of said production motors with a common source of supply of operating fluid adapted to operate said motors, at least a portion of the production flow from one of said units being converted into operating fluid and delivered to said source of supply, the production flow from another of said units being delivered to a point of discharge outside the system; and an individual pressure means associated with each of said pipes adapted to deliver said operating fluid under pressure through its said 40 pipe to the production motor connected thereto so as to operate said motor.

18. A well pumping system of the character described, including: a plurality of fluid-operated pump units placed so as to pump from a plurality 70 of wells, each of said units including a fluid-operated production motor; a pipe connecting the intake of each of said production motors with a source of supply of operating fluid adapted to operate said motors; pressure means associated with said pipes and adapted to deliver said operating fluid under pressure through its said 75 pipe to the production motor connected thereto so as to operate said motor.

- of wells, each of said units including a fluid-operated production motor; a pipe connecting the intake of each of said production motors with a source of supply of operating fluid adapted to operate said motors; pressure means associated with said pipes and adapted to deliver said operating fluid under pressure through said pipes to each of said production motors; and a transformer means in the line of one of said pipes leading to a specified production motor adapted to reduce the pressure and increase the volume of operating fluid delivered to said specified production motor.
19. A well pumping system of the character described, including: a plurality of fluid-operated pump units placed so as to pump from a plurality of wells, each of said units including a fluid-operated production motor; a pipe connecting the intake of each of said production motors with a source of supply of operating fluid adapted to operate said motors; pressure means associated with said pipes and adapted to deliver said operating fluid under pressure through said pipes to each of said production motors; and transformer means in the line of one of said pipes leading to a specified production motor adapted to increase the pressure and decrease the volume of operating fluid delivered to said specified production motor.
20. A fluid operated deep well pumping mechanism of the character described, including: a pump mechanism adapted to be placed in a well, said pump mechanism comprising a fluid motor and a pump unit connected to said fluid motor so as to be driven thereby; an operating fluid delivery pipe extending from a source of supply of operating fluid to said pump mechanism for delivering said operating fluid thereto; a governor connected to said delivery pipe so that operating fluid will pass through said governor, said governor normally maintaining the flow of operating fluid into said motor at a substantially constant rate but being constructed and arranged so that, throughout its effective operating range, it maintains such volume of flow of fluid to said motor as to maintain a substantially constant motor speed regardless of fluctuations in load on said pump; and means for manually adjusting said governor during the operation thereof so as to change the rate of flow of said operating fluid.
21. A fluid operated deep well pumping mechanism of the character described, including: a pump mechanism adapted to be placed in a well, said pump mechanism comprising a fluid motor and a pump unit connected to said fluid motor so as to be driven thereby; an operating fluid delivery pipe extending from a source of supply of operating fluid to said pump mechanism for delivering said operating fluid thereto; a governor connected to said delivery pipe so that operating fluid will pass through said governor, said governor normally maintaining the flow of operating fluid into said motor at a substantially constant rate but being constructed and arranged so that, throughout its effective operating range, it maintains such volume of flow of fluid to said motor as to maintain a substantially constant motor speed regardless of fluctuations in load on said pump; and means for manually adjusting said governor during the operation thereof so as to change the rate of flow of said operating fluid; and indicating means associated with said governor for indicating the amount of operating fluid flowing through said governor.
22. A well pumping system of the character described, including: a plurality of fluid-operated pump units placed so as to pump from a plurality of wells, each of said pump units including a fluid-operated motor, at least one of said pump units requiring operating fluid having flow characteristics different from the other of the remaining units, there being a pressure fluid inlet pipe connecting with the fluid-operated motor of each of said pump units, and there being a production discharge member associated with each pump unit; piping for receiving the production from at least one of said production discharge members; means for diverting a portion of said production from said piping; a treating device for converting said diverted portion of the production into an operating fluid for said pump units; means for conducting the operating fluid to said pressure fluid inlet pipes of said pump units, said conducting means including a compressor for placing said operating fluid under pressure so that it will operate said fluid-operated motors of said pump units; and a fluid flow governor connected with the pressure fluid inlet pipe leading to said one of said pump units and adapted to be adjusted during the operation thereof to provide a flow of pressure fluid to said one of said pump units in accordance with the required flow characteristics thereof, said governor being so arranged and constructed that, throughout its effective operating range, it maintains such volume of flow of pressure fluid to said fluid inlet pipe as to operate said pump unit at a substantially constant speed regardless of fluctuations in load on said pump unit.
23. A well pumping system of the character described, including: a plurality of fluid-operated pump units placed so as to pump from a plurality of wells, each of said pump units including a fluid-operated motor, at least one of said pump units requiring operating fluid having flow characteristics different from the other of the remaining units, there being a pressure fluid inlet pipe connecting with the fluid-operated motor of each of said pump units, and there being a production discharge member associated with each pump unit; piping for receiving the production from at least one of said production discharge members; means for diverting a portion of said production from said piping; a treating device for converting said diverted portion of the production into an operating fluid for said pump units; means for conducting the operating fluid to said pressure fluid inlet pipes of said pump units, said conducting means including a compressor for placing said operating fluid under pressure so that it will operate said fluid-operated motors of said pump units; and a fluid flow governor connected with the pressure fluid inlet pipe leading to each of said pump units and adapted to be adjusted during the operation thereof to provide a flow of pressure fluid to each of said pump units in accordance with the required flow characteristics thereof, said governors being so arranged and constructed that, throughout their effective operating ranges, they maintain such volumes of flow of pressure fluid to their associated fluid inlet pipes as to operate said pump units at a substantially constant speed regardless of fluctuations in load on said pump units.
